UNITED STATES PATENT OFFICE.

NORRIS L. O'NEILL, OF OAKLAND, CALIFORNIA, AND RICHARD R. BURKE, OF DENVER, COLORADO.

DESIGN FOR A BOTTLE.

No. 38,503.

Specification for Design.

Patented April 2, 1907.

Application filed February 21, 1907. Serial No. 358,756. Term of patent 14 years.

To all whom it may concern:

Be it known that we, NORRIS L. O'NEILL and RICHARD R. BURKE, citizens of the United States, residing, respectively, at Oakland, in the county of Alameda and State of California, and Denver, in the county of Arapahoe and State of Colorado, have invented a new, original, and ornamental Design for Bottles, of which the following is a specification, reference being had to the accompanying drawing, forming a part thereof.

The figure is a perspective view of the bottle, showing our new design.

We claim—

The ornamental design for a bottle, as shown.

NORRIS L. O'NEILL.
RICHARD R. BURKE.
